CLAIM

The ornamental design for a coil nail holder, as shown.

DESCRIPTION

FIG. 1 is a front elevational view of a coil nail holder showing my new design;

FIG. 2 is a right side elevational view, with the left side elevational view being a mirror image thereof;

FIG. 3 is a top plan view thereof;

FIG. 4 is a rear elevational view thereof;

FIG. 5 is a bottom view thereof; and,

FIG. 6 is a perspective view thereof.
